William K. Nelson(57) **CLAIM**

The ornamental design for a line tap-connector removal tool as shown and described.

DESCRIPTION

FIG. 1 is a perspective view of a line tap-connector removal tool showing my new design;

FIG. 2 is an elevation anterior view of the line tap-connector removal tool of FIG. 1;

FIG. 3 is an elevation posterior view of the line tap-connector removal tool of FIG. 1;

FIG. 4 is an elevation view of a first side of the line tap-connector removal tool of FIG. 1;

FIG. 5 is an elevation view of a second side of the line tap-connector removal tool of FIG. 1;

FIG. 6 is a top elevation view of the line tap-connector removal tool of FIG. 1; and,

FIG. 7 is a bottom elevation view of the line tap-connector removal tool of FIG. 1.

The broken lines shown in FIGS. 1-7 are for the purpose of illustrating portions of the line tap-connector removal tool that form no part of the claimed design.
